CLAIM

The ornamental design for a length measurement device for printing sheet material, as shown and described.

DESCRIPTION

FIG. 1 is a perspective view of the design for a length measurement device for printing sheet material;

FIG. 2 is a front view of the design;

FIG. 3 is a rear view of the design;

FIG. 4 is a left side view of the design;

FIG. 5 is a right side view of the design;

FIG. 6 is a top view of the design; and,

FIG. 7 is a bottom view of the design.

The broken line showing of a computer is included for illustrative purpose and forms no part of the claimed design.
